US0D1102278S

(12) **United States Design Patent** (10) **Patent No.:** **US D1,102,278 S**
(45) **Date of Patent:** **** Nov. 18, 2025**

(54) **PACKAGING BOX**

(71) Applicant: **Ciying Yan**, Jingshan (CN)

(72) Inventor: **Ciying Yan**, Jingshan (CN)

(73) Assignee: **Ciying Yan**, Jingshan (CN)

(**) Term: **15 Years**

(21) Appl. No.: **29/983,184**

(22) Filed: **Jan. 9, 2025**

(51) LOC (15) Cl. **09-03**

(52) U.S. Cl.

USPC **D9/737; D9/432**

CLAIM

The ornamental design for a packaging box, as shown and described.

DESCRIPTION

FIG. 1 is a front perspective view of a packaging box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a cross-sectional view of 9-9 in FIG. 3.

The broken lines in the drawings illustrate the portions of the packaging box, which form no part of the claimed design.

1 Claim, 9 Drawing Sheets
